UNITED STATES PATENT OFFICE.

PIO PERRONE, OF ROME, ITALY, ASSIGNOR TO SOCIETÀ ANONIMA ITALIANA GIO.
ANSALDO & C., OF ROME AND GENOA, ITALY.

MEANS OF DEFENSE FOR SHIPS AGAINST THE ATTACKS OF SUBMARINES.

1,346,720.

Specification of Letters Patent. Patented July 13, 1920.

Application filed July 24, 1916. Serial No. 111,089.

To all whom it may concern:

Be it known that I, PIO PERRONE, a subject of the King of Italy, residing at Rome, Italy, (whose post-office address is No. 366 5 Piazza Colonna,) have invented a new and useful Improvement in Means of Defense for Ships Against the Attacks of Submarines, of which the following is a specification.

10 The present invention refers to the means of defense against the attacks of submarines, consisting in a metal shield, formed by crossing several layers of steel in sheets and, in preference of steel containing vanadium.

15 It is well known that modern torpedoes are possessed of the following characteristics:

1st. That the explosion is of immense 20 power and will increase, more and more, in proportion to the progress made in fire-arms and submarines.

25 2nd. That the power of the explosion decreases rapidly according to the law of the cubes of the distances from the center of the explosion.

30 3rd. That the submarine depth at which the torpedoes are fired against big vessels (it is these ships in which the inventor is interested) is considerably lower than the immersion of the latter, in order to bring to a maximum the probability of hitting them.

35 It is also well-known that the effect of the explosion of a single torpedo against the flanks of a modern ship, however great she be, is to sink her, almost immediately.

40 Moreover modern ships having no exterior submarine point of defense, but only indirect interior protection are torn in the flanks by the explosion of the torpedo; and in consequence enormous quantities of water dash into the interior of the vessel and cause it to incline which disastrous effect is favored by the interior lateral defenses which tend to 45 arrest the progress of the water.

50 It is easy to think of an efficient protection intended to minimize the effect of the explosion of a torpedo on a ship; but that is not sufficient; for at the same time the protection must be such as not to diminish in any great measure the nautical and fighting qualities of the ship.

55 An ideal protection could be obtained by a kind of submarine basin with or without

a bottom (in which the ship could move freely) which would follow the ship and respond to her movements and against the sides of which the torpedo would be crushed.

60 It would be an independent exterior defense. Such a defense has already been studied and applied, by employing metallic nets; but the result has not been satisfactory.

65 According to the opinion of the inventor the submarine defense ought to be a part of the ship, to be in harmony with its interior construction and to be such, as to diminish but little those nautical and fighting qualities which the ship might possess without this means of defense; it ought scarcely to 70 increase the immersion of the vessel and not to diminish to a great extent, her capacities of speed and evolution.

75 It therefore follows, that the submarine protection being one with the ship, must have the following qualities:

80 1st. To be on the exterior of the shell plating of the vessel; the interior of the vessel to serve only as a strong support to the exterior protection.

85 2nd. To be of great thickness so as to keep as much as possible the center of the explosion of the torpedo far away from the shell plating.

3rd. To be massive and of such kind that its tearing will not produce practically any heeling of the ship.

90 4th. To be a continuous mass of great inertia, so as to be able, by its inertia, to absorb a great part of the energy of the explosion, before it can produce its effects upon the shell plating of the hull.

95 5th. To be relatively light, so as not to increase the immersion of the vessel.

6th. To have such a structural inertia as to be able to resist the effects of the explosion and to be able to disperse them over a more extensive zone of the flanks of the vessel.

100 7th. To be plastic so as to act as a stopper against the inlet of the water, in case cracks should be produced in the shell plating by the force of the explosion.

105 8th. The exterior form of the defense should be such, as to offer but little resistance to the movements and evolutions of the ship.

9th. The interior construction must be

strong enough to be able to well support the exterior protection, and to prevent the same being forced in as a whole and such as not to prevent the free passage of the water 5 from one side to the other side of the vessel, in the case that the shell plating, in spite of its exterior protection, should be damaged.

One and all of these qualities have been 10 acquired in the protection which has been studied and which is the object of the present invention and is illustrated by way of example in the accompanying drawing, in which:

Figure I is a cross section of the vessel, 15 and

Fig. II is a section on the line M N of Fig. I.

The protection is entirely on the exterior 20 of the vessel and is constructed thus:

20 1st. By reinforced shell plating A formed by several superposed layers of ordinary steel plates, crossed over each other, or, better still of special high grade steel, as, for example, vanadium steel.

25 2nd. By a thick layer B of pitch applied to the exterior of the shell plating and upheld by light vertical frames, which will serve to strengthen the said armored shell plating and also as a support for the rest of 30 the protection as shown in the drawings.

3rd. By strong wooden planking of thick timber C, placed longitudinally and fixed to the above mentioned vertical frame, the whole being thoroughly calked.

35 4th. By a second strong planking D of vertical wooden timbers, applied to the preceding longitudinal frame, and being also calked.

40 5th. By a third layer E of longitudinal wooden thick timber planking applied to the preceding vertical frame and also calked.

The superposition of the wooden layers 45 could be continued, but the above-mentioned layers are sufficient against torpedoes; even if they were more powerful than the present ones.

50 6th. By a frame of zinc plates O applied to the exterior of layer E to provoke the explosion of the torpedo on the exterior and to protect the timber planking from sea-weed.

The said protection is extended in height 55 from above the water line to under the turn of the bilge where it terminates in a big and strong bilge or side keel H, which forms a support to the said protection and which breaks the wave of the explosion of the torpedo, so that it cannot extend under the bottom of the ship, which bottom is however 60 protected, although to a less extent near its said bilge keel H by a reinforced shell plating and by a strong timber planking I.

Nothing would prevent however the lateral 65 protection from being continued even

below the bilge keel, at least for a certain length, if it should be convenient. Longitudinally the protection extends from the stern to the bow, narrowing off toward the extremity of the bow where there are practically no vital parts, and modified at the stern so as to protect the helm and the screw, without interrupting their action. 70

It is not necessary that the reinforced metallic plating, the layer of pitch and the layers of timber should follow in the above mentioned order. They might be interchanged without diminishing the efficiency of the protection but the foregoing arrangement appears to be the best. 75

Having now particularly described the nature of my said invention and in what manner the same is to be performed, I declare that what I claim is:

1. A defense for ships against the attacks 80 of submarines comprising in combination a hull structure, a plurality of crossed steel plates applied to the exterior of the hull, vertical frames on the exterior of the said crossed steel plates, a thick layer of pitch held in place by the said carrying frames, longitudinal timber planking carried by the said vertical frames and a second vertical timber planking applied to the preceding longitudinal planking and well calked. 90

2. A defense for ships against the attacks 95 of submarines, comprising in combination a hull structure, a plurality of crossed steel plates applied to the exterior of the hull, vertical frames on the exterior of the said steel plates, a thick layer of pitch held in place by the said frames, longitudinal timber planking carried by the vertical frames, vertical timber planking applied to the preceding longitudinal planking and a second 100 layer of longitudinal timber planking applied to the preceding vertical planking and well calked.

3. A defense for ships against the attacks 105 of submarines comprising in combination a hull structure, a plurality of crossed steel plates applied to the exterior of the hull, vertical frames on the exterior of the said steel plates, a thick layer of pitch held in place by the said frames, longitudinal timber planking carried by the vertical frames, vertical timber planking applied to the preceding longitudinal planking and a second layer of longitudinal timber planking applied to the preceding vertical planking and well calked, and a sheathing of zinc plates 115 which serves to cause the explosion of the small fore charge of the torpedo and to protect the wooden planking from seaweed. 120

4. A defense for ships against the attacks 125 of submarines comprising a hull structure, a plurality of relatively crossed vanadium steel plates applied to the exterior surface of the hull, vertical frames on the exterior of the steel plates, a plastic layer applied to 130

the exterior of the steel plates and supported by the vertical frames, a plurality of layers of relatively crossed timber planking and an exterior sheathing of zinc plates, 5 the whole forming a reinforcement and protecting system to the said hull.

In testimony whereof I have signed my

name to this specification in presence of two subscribing witnesses.

PIO PERRONE.
